ATTORNEY S.

UNITED STATES PATENT OFFICE.

SAMUEL S. REESE, OF BROOKLYN, NEW YORK.

LOOSE-LEAF CONTAINER.

Application filed October 2, 1926. Serial No. 139,102.

My invention relates to a new and improved loose leaf container or drawer for use in loose leaf filing cabinets or the like.

One of the objects of my invention is to provide a new and improved container or drawer for loosely holding a number of sheets in the form of a vertical or inclined group.

Another object of my invention is to provide a container or drawer which shall be laterally extensible so that the holder can accommodate loose leaves of varying width.

Another and even more important object of my invention is to provide a container or drawer which can be laterally extended so that selected sheets of the group can be distinguished from the others by laterally displacing said selected sheets.

Another object of my invention is to provide a device of this type which shall be of simple and durable construction.

Other objects of my invention will be set forth in the following description and drawings which illustrate a preferred embodiment thereof, it being understood that the above general statement is intended merely to generally explain the same and not to limit it in any manner.

Fig. 1 is a section on the line 1—1 of Fig. 2.

Fig. 2 is a top view, part of the bottom of the device being broken away to show some of the operating parts.

Fig. 3 is a section on the line 3—3 of Fig. 1.

Fig. 4 is a side elevation partially in section.

Containers or drawers for holding loose leaves comprising box-like casings and provided with supports for holding groups of loose leaves in vertical or slightly inclined position have been well known for many years. In order to readily identify selected leaves of said group, it has been customary to provide vertically projecting markers of various types. These markers have been an additional source of expense and labor, and in addition serious errors could arise if some of said markers were accidentally removed.

According to my invention, the said case or holder, including the cover therefor, is laterally extensible, so that selected sheets of the group can be laterally displaced and thus be readily distinguished from the other sheets of said group.

As shown in Figs. 1 and 2, the container or drawer comprises a box-like structure 10 made of any suitable metal and provided with

front and rear walls 11. This casing may be provided with a pair of front and rear left-hand supports 30 and a similar pair of right-hand supports 38. As shown in Fig. 2, the tops of the front and rear walls 11 are bent over to form U-shaped guides. The lateral walls of the container 10 fit within said U-shaped guides so that they can be slid laterally to and fro.

As shown in Fig. 2, a shaft 24 provided with threaded ends 24^a at the front and rear thereof is mounted in bearing members 34, one of these bearing members being preferably provided in the central part of the device, and two like bearing members being provided at the front and rear of the device. The front and rear externally threaded portions 24^a of the shaft 24 co-operate with nuts 26 and 27' and these are pivotally connected to links 28 and 29', by means of pins 32 and 33' which are also connected to intermediate members 30 and 31'. The links 28 and 29' are pivotally connected to the bottoms of the lateral walls 12, as shown more particularly in Figs. 2 and 3. The links 28 and 29' are upwardly bent, as shown in Fig. 1.

The shaft 24 can be turned by means of a crank 36 which fits over and co-operates with a projecting and non-circular end 35 of the shaft 24.

Hence, when the crank 36 is turned, the pairs of links 28 and 29' operate to simultaneously and equally move the lateral walls of the box in opposite directions, because the nuts 26 and 27' are simultaneously moved in opposite directions due to the fact that the threaded ends 24^a of the shaft 24 are threaded in opposite directions.

A U-shaped bottom member 18 is adapted to rest upon the bottom of the container 10 and cover the operating mechanism for moving the lateral walls of the container. This bottom member 18 is provided with vertically disposed slides 14 and 15 which slide upon longitudinal rods 22 suitably connected to the bottom member 18. The front slide 14 can be clamped against the bottom member 18 by means of the lever 16 pivotally connected to the front slide 14 at 16', and adapted to abut a stop 17 connected to the said front slide 14. The lever 16 acts as a latch member whose forwardly bent bottom frictionally engages the bottom member 18 when said lever 16 is moved to the position shown in Fig. 1. When the member 16 is forced into

100

105

110

the position shown in Fig. 1, the upward movement of slide 14 is prevented by rods 22 which fit in openings in slide 14.

5 A group of loose leaves S can be held between the slides 14 and 15.

The bottom member 18 is provided with central hollow and internally threaded posts 20 by means of which said bottom member can be firmly held in position by means of 10 suitable lock nuts 21 which pass through suitable openings in the bottom of the container 10.

15 The cover 12 of the box has a similar construction so that it can also be laterally extended. Said cover is provided with end walls 13 in which the lateral walls of the said cover can be slid to and fro. The cover also has a shaft 25 similar in construction to the shaft 24, and the shaft 25 co-operates 20 with nuts 27 similar to the nuts 26 and 27', and said nuts 27 co-operate with pairs of links 29 similar to the links 28 and 29' before mentioned, said links 29 being connected by pins 33 to intermediate members 31, in 25 the manner before mentioned. The cover is also provided with a U-shaped top member 19 which encloses the operating mechanism for said cover.

It is obvious that the said compartment 30 may be used as a drawer in a filing cabinet, for example, or independently thereof, and that the width of the container or drawer may be readily increased so as to enable selected leaves S to be laterally displaced.

35 I have shown a preferred embodiment of my invention, but it is clear that numerous changes and omissions could be made without departing from its spirit.

I claim:—

40 1. A tray for holding loose leaves comprising a box-like member, the said member having a laterally movable side wall and means adapted to adjust the distance between said side walls and to hold them in adjusted position.

45 2. A tray for holding loose leaves comprising a box-like member having a laterally movable side wall and a shaft having an externally threaded portion and connected to said box-like member, and connecting means between said externally threaded portion of the shaft and said side wall, said last mentioned connecting means being adapted to cause the actuation of said side wall when the said shaft is turned.

50 3. A tray for holding loose leaves comprising a box-like member having laterally movable side walls, a shaft connected to the

bottom of said box-like member, said shaft having externally threaded portions threaded 60 in opposite directions, nuts respectively connected to the said externally threaded portions and adapted to be moved in opposite directions when the said shaft is turned, and links respectively connected to the said nuts 65 and to the said side walls to simultaneously and equally actuate said side walls in opposite directions.

4. A loose leaf holder comprising a box-like member and a cover therefor, the side 70 walls of said box-like member and of said cover being laterally movable to and fro, longitudinal shafts respectively connected to the bottom of the said box-like member and to the top of the said cover, each said shaft having externally threaded portions threaded in opposite directions, nuts connected to the threaded portions of the said shafts, the said nuts having links connecting each of them to the respective side walls of the said member 75 and the said cover, whereby the turning of the said shafts laterally actuates the said side walls.

5. A tray for holding loose leaves comprising a box-like member having front and 80 rear walls, the said member having laterally movable side walls provided with lateral extensions adapted to abut the said front and rear walls, to present a complete box-like structure when the said lateral walls are 85 laterally adjusted.

6. A tray for holding loose leaves comprising a box-like member having front and rear walls whose tops are bent over to form U-shaped guides, the said member having 90 laterally movable side walls, the said side walls being provided with a lateral extension adapted to slide within the said U-shaped guides.

7. A tray for holding loose leaves comprising a box-like member having laterally 100 movable side walls, a shaft connected to the bottom of said box-like member, said shaft having externally threaded portions threaded 105 in opposite directions, nuts respectively connected to said externally threaded portions and adapted to be moved in opposite directions when the said shaft is turned, said shaft being enclosed by a U-shaped bottom member having a horizontally adjustable 110 slide connected thereto, and links respectively connected to said nuts and to said side-walls to simultaneously and equally actuate said side walls in opposite directions.

In testimony whereof I affix my signature.
SAMUEL S. REESE.
